Design U.S. Appl. No. 35/503,123, filed Feb. 28, 2017.

Primary Examiner — Richard E Chilcot(74) *Attorney, Agent, or Firm* — Margaret Polson; Polson Intellectual Property Law, PC(57) **CLAIM**

The ornamental design for a mobile service robot, as shown and described.

DESCRIPTION

1.-2. Mobile service robot

1.1 is a front perspective view of my new design for a mobile service robot

1.2 is a front side elevation view of Figure 1.1

1.3 is a back side elevation view of Figure 1.1

1.4 is a left side elevation view of Figure 1.1

1.5 is a right side elevation view of Figure 1.1

1.6 is a top side plan view of Figure 1.1

1.7 is a bottom side plan view of Figure 1.1

1.8 is a perspective view of Figure 1.1 in the state of use.
